UNITED STATES PATENT OFFICE.

CHARLES T. WITTSTEIN, OF NEWARK, NEW JERSEY.

JEWELER'S TAG.

No. 899,778.

Specification of Letters Patent.

Patented Sept. 29, 1908.

Application filed March 2, 1907. Serial No. 360,128.

To all whom it may concern:

Be it known that I, CHARLES T. WITTSTEIN, a citizen of the United States, residing at Newark, in the county of Essex and 5 State of New Jersey, have invented certain new and useful Improvements in Jewelers' Tags, of which the following is a specification.

This invention relates to tags intended for 10 temporary attachment to finger rings and various other articles of jewelry, and comprises a tag coated with adhesive material to facilitate quick and easy attachment to the ring or other article of jewelry to be marked, 15 and provided with attaching means quickly and readily adjustable to different sizes of articles and constituting part of the material of the tag itself.

The objects of my invention are, to improve 20 and simplify tags such as described; to enable same to be quickly and readily applied to articles of widely different sizes; to cause the attaching means of the tag to grip closely, without actually adhering to, the 25 object to which it is attached, so preventing undue motion of the tag with reference to its support; and generally, to produce a simple, inexpensive, and easily applied tag for the purpose described.

30 I will now proceed to describe my invention with reference to the accompanying drawings, in which one form of tag embodying my invention is illustrated, and will then point out the novel features in claims.

35 In said drawings: Figure 1 shows a plan view of the tag opened out but ready for use. Fig. 2 shows a side view of the said tag, the thickness of the layer of adhesive being considerably exaggerated in this figure. Fig. 3 shows an edge view of the tag closed and applied to a ring, which latter is shown in section, dotted lines indicating in this figure how the tag may be adjusted to a much larger ring. Fig. 4 shows a top view 40 of the ring and tag of Fig. 3, and dotted lines in this figure, as in Fig. 3, indicate how the tag may be adjusted to a much larger ring. Fig. 5 shows an edge view of the tag with the sealing flap bent over but unsealed, and 45 with the attaching strip bent over into a loop, dotted lines indicating how this attaching strip may be caused to form a larger loop.

The tag shown in the drawings comprises 50 two main sections or lobes, 1, 2, having a weakened connection as at 3 so that lobe 2

may be folded over on to lobe 1, and comprises also a connecting or attaching strip 4 extending from lobe 1. These two lobes and the attaching strip are all formed, preferably, from the same piece of paper, cloth, or other suitable tag-material. One, and, preferably, both, of the lobes are provided with a coating or layer of adhesive material, such as mucilage, indicated in Figs. 1 and 2 by reference numeral 5; the thickness of this coating or layer of adhesive material being greatly exaggerated in Fig. 2, to make it apparent.

Rings, pins, bracelets, and other objects to 70 which tags such as these are intended to be applied, vary greatly in size. It is desirable that the tag shall be fastened quite tightly to the object to which it is applied, so that the tag may not swing freely; for if it 75 does swing free, it is apt to come off, in the case of pins, or is apt to be crumpled, broken, or torn, in the case of rings or bracelets. But it is quite important that the tag shall not be absolutely adherent to the metal surface (as 80 might be the case, for example, if there were adhesive material on the portion of the tag next the metal) for if such were the case the metal might be tarnished or its polish impaired. The attaching strip 4 constitutes an 85 exceedingly satisfactory means for attaching the tag to the ring or other article; for it may be of any desired length, and so may be long enough to be wrapped around the largest object to which the tag is to be attached, and 90 yet will not be too long to hold as tightly to the smallest ring or pin; but since this strip has no adhesive on its surface, it cannot tarnish or mar the polish on the metal about 95 which said strip is wrapped.

In the use of my improved tag, the adhesive surfaces of the lobes 1 and 2 are moistened, the attaching strip 4 is passed around the ring or other object to which the tag is to be fastened and then is pressed down upon the adhesive surface of lobe 1, being drawn tight around the ring or other object, as illustrated, so that the tag will be fastened quite tightly thereto; and then the lobe 2 is pressed down upon the end of said strip 4 and upon 100 the adhesive surface of lobe 1, the two adhesive surfaces immediately uniting and so sticking the two lobes firmly together. When the adhesive has dried and set it 105 stiffens the tag materially when the latter is of paper or fabric, thus making an excellent and durable tag for the writing of prices, size 110

and other useful memoranda thereon. 6, in Figs. 3 and 4, indicates such a ring, and 6^a indicates (in dotted lines) a larger ring. In Fig. 5, 7 designates the bight of the attaching strip required to surround a small article, and 7^a designates a larger bight of such strip (indicated in dotted lines) required to surround a larger article.

It will be noted that the adhesive coating 10 of the lobe 1 extends to the line of joining of the attaching strip 4 with the said lobe, and furthermore that the adhesive coating on the lobe 2 extends clear to the edge thereof which when the two lobes are folded together 15 is adapted to coincide with the line of joining of the attaching strip to its lobe 1. The result of this construction is that when the said parts are folded together into the completed tag, the two arms or sides of the loop which 20 the attaching strip forms, are secured to the tab or body portion at exactly opposite points, and there is therefore no unevenness

either of strain or in the position which the tag naturally assumes.

What I claim is:—

25 A jeweler's tag comprising a piece of flexible material having lobes with a weakened connection which predetermines a line of folding and an attaching strip projecting from one of said lobes independent of the 30 said connection and adapted to be bent around a body to which the tag is to be applied and folded over upon the lobe to which it is attached, said lobes being adapted to be brought flatwise together by folding and 35 form a display tab, and a layer of adhesive matter on one of said lobes at one side surface of the tag, the attaching strip being devoid of such adhesive matter, as and for the purposes set forth.

CHARLES T. WITTSTEIN.
